UNITED STATES PATENT OFFICE.

CHARLES C. THORN, OF CAMDEN, NEW JERSEY.

SWITCH THROWING AND LOCKING MECHANISM.

Application filed April 8, 1926. Serial No. 100,473.

My invention relates to switch operating and control mechanism for railway track use, best suited to cross-overs and turnouts.

One purpose of my invention is to simplify operation and to improve the protection given against inconsistent operation of separate switches and/or switches and derails.

A further purpose is to provide an improved switch and throwing mechanism, well suited to use where locking or electrical indication control is needed.

A further purpose is to control a siding derailing device by the switch controlling admissions from the main track to the siding.

A further purpose is to control the switch between a main track and a siding by the position of the siding switch and a derailing device or other switch inter-related with the first switch.

A further purpose is to additionally protect switch mechanism controlled by a center locking lever.

A further purpose is to remove the pounding effect of passing trains from the operating mechanism of a switch and take it up in the body of the switch, at the same time avoiding risk of the pounding reversing the position of the throwing lever.

A further purpose is to lift the operating mechanism out of the water and dirt of the track.

A further purpose is to operate a switch by a gear-operated plate cam through a crank with which the cam engages.

A further purpose of this device as provided at the switch involves means of operating and permissibly locking the switch by the use of one hand lever, and to include therein contacts so that a track circuit if used will be shunted before the switch is unlocked, insuring that all signals involved will be returned to their most restrictive indication.

Further purposes will appear in the specifications and in the claims.

I prefer to illustrate my invention by a single form only among the various forms in which it may appear, selecting one which is practical, effective and reliable and which at the same time well illustrates the principles involved.

Figure 1 is a top plan view of a switch-operating mechanism and circuit controller embodying my invention, the top of the cir-

cuit controller being removed for clearness.

Figure 2 is a side elevation of the structure seen in Figure 1 with the top in place.

Figures 1^a, 1^b, 1^c and 2^b, 2^c correspond in part with 1 and 2, respectively but are fragmentary, on reduced scale and show modifications of the parts.

Figure 3 is an enlarged fragmentary section of Figure 1 taken upon the line 3—3.

Figure 4 is a fragmentary section of Figure 1 upon line 4—4.

Figures 5, 6 and 7 are fragmentary top plan views of tracks and switches to which my invention may be applied.

In the drawings similar numerals indicate like parts.

With the arrangement at present generally in use on a turnout from main track to siding when the switch has been reversed and the derail has been taken off the track, the switch can be put back to normal and the train can go away leaving the derail for the siding off the track. This makes it possible for a car or cars on the siding to drift on to the main track, which would be particularly dangerous if track circuits were not used. It is necessary with the existent arrangement for the train man to manipulate his switch key twice to unlock the levers. These objections have been corrected by me by throwing the derail from the switch and, correspondingly, one lock only is required.

In the case of a cross over between a main track and a siding, with the arrangement at present generally in use the switch in the main track may be put to normal after having been reversed and the train may then leave without putting the siding switch in its normal position and without throwing the locking lever to lock both switches. This leaves the main track switch unlocked and would allow a car to drift out from the siding to the main track. This objection has been overcome by me by requiring the replacement of the siding switch to normal, after it has been thrown, before the main track switch can be replaced to normal and by insuring that the signals involved shall return to their most restrictive indications.

In the case of a cross over between main tracks, the device at present in general use requires a facing point lock and circuit controller at each end of the crossover and a switch throwing device, which are combined in a single device in the new mechanism.

My switch throwing mechanism is shown in Figures 1 and 2 as mounted within a casing 9, adapted to be held in place by apertured lugs 10. It is protected by cover members 11 and 12 and a gear casing 13, which may be combined with one of the cover members.

The interior of the casing receives and guides a sliding plate 14 having gear teeth 15 upon its upper surface and a cam slot 16 within its lower surface. The cam slot comprises terminal straight locking portions 17 and 18 and an intermediate diagonal operating portion 19 bounded by cam surfaces 20 and 21. The straight portions 17 and 18 are bounded by parallel edges 22, 23, 24 and 25.

The sliding plate 14, referred to herein also as a cam plate because it carries the cam, is connected in any suitable way as by rivets 26 with a bar 27 apertured at 28, which bar is connected in different forms of my invention with switches or other apparatus which are to be thrown by this operating mechanism or which exercise a control over it or are controlled by it.

On opposite sides of the device shown in Figures 1 and 2 are located pillow blocks 29 provided with caps 30, forming bearings 30 for a shaft 31 upon which are rigidly mounted a segmental gear 32 engaging with rack 15 and a switch lever 33 by which the gear is turned to throw the rack to the right or to the left of its normal position.

Within the cam slot 16 I place a pin 34 mounted upon a crank 35 carried by shaft 36. Upon the outer end of this shaft is keyed switch operating arm 37 apertured at 38 and adapted to be connected in any suitable way with the switch to be thrown.

In operation, as so far described, the members are shown in the drawings in the normal position in which the switch is locked and in which the switch throwing lever 33 is in fact locked. The switch connections are made through arm 37.

When the operating lever 33 is thrown upwardly and to the left from the position shown in Figure 2 the segmental gear engages the rack carrying it to the right. This first causes the straight portion 18 of the cam slot to pass lengthwise of the pin 34 and subsequently causes the cam surface 20 to bear upon the pin and force the pin toward the bottom of the sheet in Figure 1 until it is in line with the straight part 17 of the cam slot. The fact that the portions 17 and 18 are straight causes continued movement of the cam plate to lock the pin 34 without further turning of the pin after it has been thrown by either cam surface, and continued movement of the cam plate therefore locks the pin within the straight portion 17. The bar 27 has meantime been moved to the right in the figures.

Reversal of throw of switch-throwing arm 33 unlocks the pin, throws it in clockwise direction by means of cam surface 21 and locks it again within the portion 18 of the slot, meantime turning switch lever 35 in clockwise direction (Figure 1) and moving bar 27 to the left as seen in Figures 1 and 2.

The straight sides of the portions 17 and 18, substantially perpendicular to the direction of rotation of pin 34 where it engages them, relieve the cam plate from strain in a direction parallel to its direction of movement and avoid any tendency to reverse the lever in the two positions in which it is intended to be thrown. It thus transfers any reversing pressure to the casing.

The cover 11 may merely complete the cover of the casing or frame when no electrical control is intended or, as shown in the illustration it may form the means of mounting an electrical control shown at the left in Figures 1 and 2 and shown in more full detail in Figures 3 and 4. In this latter case the rack bar carries a slide 39 shown as riveted to it.

The slide 39 is adapted to pass through notches in the facing point switch bars 40 and 41 so as to lock them in the position shown in Figures 1 and 2 but to release these lock bars when the lever 12 is swung to the left in these figures.

Where no electrical control is to be used the structure terminates at this point. For electrical control a cam dog 42 is secured to the slide bar 39 as by riveting at 43. This cam dog controls the position of a rocking lever 44 pivoted at 45 so as to rock the lever about the pivot. One cam face 46 engages the corresponding face 47 of the rocking lever to tilt the lever in clockwise direction (Figure 3) into the position seen in this figure when the switch throwing lever is being thrown in clockwise direction as measured in Figure 2. The other cam face 48 engages with a cooperating face 49 upon the lever to swing it in counter-clockwise direction with reverse, that is counter clockwise swinging movement (Figure 2) of lever 33.

The pivot 45 receives bearing support in a special cover 50 used when electrical connections are to be made by this switch. The cover is extended to provide a box 51 within which are lead conductors 55, 56 suitable interior connecting wires and the contacts 57, 58. Normal contacts 57 of any suitable number are connected together into two groups as by plates 59 and 60 but require no insulation as their multiplicity is for the purpose only of insuring good contact. Likewise the contacts 58, though insulated from contacts 57 and from each other by a block 61 ordinarily require no insulation as the complete return from the contacts 57 is made through them. Ad-

ditional openings 62 appear in the bottom of the box for any extra contacts that are to be made. The wires through them may be insulated or not as the circuits require or permit.

Connected with the cover 50 in any suitable way is a plate 63 carrying a guide 64 for post 65. The post terminates in a frame 66 by which the contact fingers 57 are lifted and lowered so as to disengage from or engage with contact fingers 58. The post 65 is connected in any suitable manner at 67, here by a pivot, with one end of the rocking lever 44 with the result and effect that clockwise rocking movement of the lever 44 lifts the post and separates contact fingers 57 from contact fingers 58, whereas counter clockwise tilting movement of this lever lowers the post 65 and lowers the contact fingers 57 into engagement with contact fingers 58.

The cover 68 is hinged at 69 so as to make the parts quite accessible when the cover is opened and is latched by a catch 70 swung from straps 71 and engaging over hook 72, forming a catch such as is used generally on refrigerators. The latch slips over a hasp eye 73 permitting locking of the parts.

Figure 1^a is intended to be identical with Figure 1 in the portion shown except as bar 27 is cut or interrupted at 74 so that the inner end 27¹ can shove the outer end 27² to the right of the figure or can prevent replacement of the outer end if the latter has been moved to the right. Where a main track switch and siding switch are to be used for a cross over, for example, an individual bar of the main track switch throwing mechanism may be connected to the cut end 27² of the siding switch throwing mechanism so that the siding switch can not be thrown until the main track switch has been thrown to move this portion 27² out of the way. Likewise when the siding switch has been thrown the main track switch can not be replaced until the siding switch has been returned to position.

Taking up the application of my invention to derail controls at sidings and at crossovers, I show the invention applied to control of a derail in Figure 5 where the main track is shown above, the siding below, and the two ends of the connection are shown complete with a short intermediate section, showing those portions of the track at which the bell cranks are placed for change of direction of pull and thrust of the operating pipe connections.

The switch points 75 are connected as usual by front and lock rod 76, operating signal light 77 and lock bars 40, 41. The switch throwing mechanism shown in Figures 1 and 2 may be used with or without the attachment for electrical connections, operating rod 78 being thrown by switch operating

crank 37. In this Figure 5 the switch throwing lever 33 has been placed on the opposite end of the pin 31 from its position in Figures 1 and 2.

With the parts in the position shown, an undercut for 27 of my switch throwing mechanism is connected with derail point 79 by piping 80, 81 and 82, bell cranks 83, 84, 85 and operating rod connections 86. The derail is set in Figure 5 for derailing. When the switch throwing lever is thrown to the left of Figure 5 the switch is operated to connect the main track with the siding and the derail is thrown "off", that is set to permit this connection. With replacement of the switch throwing lever the switch in the main track will be thrown into the position shown and the derail will again be set for derailing. The result would be the same whatever the type of derail used but the character of movement would have to correspond with the derail used.

In Figure 6 are shown a main track below and a siding above, for which two switch operating mechanisms are used to control a crossover. In these the operating mechanism at the right controls the main switch and is correspondingly placed as shown. In the switch at the upper left, controlling the siding, the bar 27 is cut as in Figure 1^a so that, as explained above, the throwing of the main switch must take place to move the outer end 27² of its bar before the siding switch can be thrown to open the track to the siding, and, correspondingly, the siding switch must be replaced before the main track switch can be replaced. The piping connections 80, 81, 82 and bell cranks 83 and 84 have been traced from the main switch operating mechanism in this case, corresponding to their tracing from the only switch operating mechanism in Figure 5.

In the crossover shown in Figure 7 the end omitted at the left is a duplication of that shown except that the illustration would be turned through an angle of 180 degrees. Here the rules of the best railroads require a little different arrangement of the parts in view of the fact that two main tracks are involved and that in operation there must be protection from throwing of the switches while a car is on the crossover.

I therefore show the required lock-bar-locking lever 87, throwing rods 88, 89, 88', 89' and bell cranks 90 by which the locking impulse for the two switches is effected and the signals are cleared. This operating part is old in the art but the application to or rather through my mechanism is new.

The switch operating mechanisms at the two switches are intended to be alike and need perform no other function here than the actual throwing of the switch. However, they are desirably altered as in Figures 1^b and 2^b to permit the same locking mechanism

and circuit controller to be used as in the other forms. No change is required except to substitute a new bar 39' for the bars 27 and 39, passing it through the mechanism over the rack and free from attachment to the rack.

In the switch throwing mechanism 9' used in each of these switches and shown in Figures 1^b and 2^b, the motion plate carrying the rack and cam is unchanged but the rod 89' connects with a bar 39' which passes through above the rack. The segmental gear 32 is displaced laterally to permit this bar 39' to pass to one side of this gear. The bar 39' is also cut at the edge at 91 to allow more room and is additionally recessed at 92, providing a "step" at 93 for the purpose of interlocking the locking lever 87 and its connections with the two switch throwing mechanisms.

This interlocking is secured by passing a stop lug 94 upon the side of the segmental gear in such position that when the locking lever 87 is thrown to pass the bar 39' into the apertures in lock rods 40 and 41 the stop lug 94 will lie over the "step" 93 preventing movement of the switch throwing lever 33 and effectually protecting against the switch throwing mechanism bringing any strain upon the switch. The stop lug is effective to block movement of the lever much before the lever would cause movement of the motion plate to clear the pin 34 of the straight part of the slot and therefore blocks turning movement of the switch throwing lever before the cam surface of the motion plate engages this pin 34.

It will be obvious that the direction of movement of the switch throwing lever may be reversed by mere reversal of the direction of the cam groove in the cam plate, that the 27, cut or uncut extensions or/and that the switch throwing lever may be placed upon either end of the shaft 31, all as indicated in Figure 1^c and 2^c, providing for a great variety in the relations of the movements secured to suit the needs of any location that may be desired beside the track and to provide any interconnection or interlocking of the parts with other switch operating mechanism which may be sought.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:—

1. In an operating mechanism for switches, an operating lever, a gear rotated thereby, a

rack engaged by the gear and carrying an eccentric therein having operating faces effective with movement in opposite directions and holding faces effective at the end of each movement, a rocker shaft having a portion cooperating with the cam by which it is thrown and held in position as thrown and a crank on said rocker shaft adapted for connection to throw a switch.

2. In an operating mechanism for switches, an operating lever, a gear rotated thereby, a rack engaged by the gear and carrying a cam therein having operating faces effective with movement in opposite directions and holding faces effective at the end of each movement, a rocker shaft having a portion cooperating with the cam by which it is thrown and held in position as thrown and a crank on said rocker shaft adapted for connection to throw a switch, said crank operating in a plane perpendicular to the plane of operation of the switch throwing lever.

3. In switch throwing mechanism, a pivoted switch throwing lever movable in a vertical plane parallel to the track, a gear operated by the lever, a rack moved by the gear, a cam carried by the rack, a switch-operating crank moved by the cam toward and from the track and an operating bar carried by the rack plate and movable along the track divided in two parts each part operating as a check upon or movable by the other part.

4. In switch throwing mechanism a pivoted switch throwing lever movable in a vertical plane parallel to the track, a gear operated by the lever, a rack moved by the gear, a cam carried by the rack, a switch operating crank moved by the cam toward and from the track and an operating bar carried by one end of the rack movable along the track and switch-locking mechanism at the opposite end of the rack.

5. In switch throwing mechanism, a pivoted switch throwing lever movable in a vertical plane parallel to the track, a gear operated by the lever, a rack moved by the gear, a cam carried by the rack, a switch-operating crank moved by the cam toward and from the track and an operating bar carried by one end of the rack and movable along the track, locking mechanism at the opposite end of the rack, a cam carried by the lock mechanism, a rocking lever swung by said cam and connections whereby electric contacts are made and opened with rocking movement of the rocking lever.

6. In switch throwing mechanism, a frame, a rack plate guided within the frame, a gear connected to engage the rack, and throw it, a shaft for the gear, a switch-throwing lever upon the shaft, cam surfaces and locking surfaces carried by the rack, a lever arm cooperating with the cam to be thrown by it and held in position at both

ends of the throw, a shaft for the lever arm, a switch-operating crank upon the shaft movable in a horizontal plane toward and from the track, connections from the crank to throw the switch, lock rods movable with the switch and a lock bar carried by the rack plate engaging with the lock rods.

7. In switch throwing mechanism a frame, a rack guided within the frame, a gear connected to engage the rack and throw it, a shaft for the gear, a switch-throwing lever upon the shaft, cam surfaces and locking surfaces carried by the rack, a lever arm cooperating with the cam to be thrown by it and held in position at both ends of the throw, a shaft for the arm, a switch-operating crank upon the shaft movable toward and from the track, connections from the crank to throw the switch, lock rods movable with the switch a lock carried by the rack engaging with the lock rods and a second switch member operated by the pull and thrust of the rack.

8. A switch throwing lever, a plate operated thereby, switch throwing connections from said plate, a cam, operated by the plate, a rocking lever pivoted near the cam having cam engaging devices at opposite sides of its pivot point, guided contact-making and breaking devices and connections between said devices and one end of the lever, whereby operation of the cam tilts the lever and lifts or lowers the contact-making devices.

9. In a switch throwing mechanism, a switch throwing lever, a gear retarded thereby, a rack engaged by the gear, a cam movable with the rack and having intermediate operating faces and end holding faces, a rocker shaft having an arm engaged by said cam and a second arm adapted to throw a switch and a locking connection with said rack adapted to engage the lock rods of the switch at one end of its stroke and be released from them at intermediate times, and at the other end of said stroke.

10. In a turn out from a main track to a siding, a main track switch, a switch-throwing lever, a plate reciprocated thereby, a derail, thrust connections from the plate to the derail, a cam carried by said plate, a switch throwing crank connected with the switch, operated by the cam and held in locked position at the extremities of the cam movement, a lock rod connected with the switch and locking mechanism carried by the plate and adapted to engage the lock rod.

11. In a turn out from a main track to a siding, a main track switch, a switch-throwing lever, a plate reciprocated thereby, a derail thrust and pull connections from the plate to the derail, a cam carried by said plate, a switch-throwing crank connected with the switch and operated by the cam, a lock rod connected with the switch and lock-

ing mechanism carried by the plate end engaging the lock rod.

12. In a cross-over from a main track to a siding, a main track switch, a siding switch, a main track switch operating mechanism comprising a switch-throwing lever, a plate reciprocated thereby, a cam carried by the plate, a switch-operating crank arm moved by said cam, connections to the switch, locking mechanism for the switch carried by the plate, a siding switch comprising a switch-throwing lever, a plate reciprocated thereby, a cam carried by the plate, a switch throwing crank arm operated by the cam, connections to the switch, and a lock for the switch carried by the plate, connections between the switches comprising bars in line of reciprocation both connected with the plate and one cut to free the outer part from the part operated by the plate and connections between the outer ends of the two bars whereby the throwing of the siding switch from normal is prevented until the throwing of the main switch has moved the outer part of the siding switch bar, and the throwing of the siding switch causes the inner end of the bar upon the siding switch plate to interfere with movement of the main track switch to normal by interference with the movement of the outer part of the bar until the side track switch is replaced to normal.

13. In a cross-over from a main track to a siding, a main track switch comprising switch throwing and locking mechanism and a bar reciprocated by movements of the mechanism, a main track switch thrown thereby, a side track switch, a side switch throwing and locking mechanism having a bar moved thereby and connections from the bar of the main track switch into the path of movement of the bar of the side track switch preventing movement of the side track switch from normal until the main track switch has been thrown from normal and, when the side track switch has been thrown from normal, preventing replacement of the main track switch to normal until the side track switch has been replaced.

14. In a cross-over from a main track, the combination of main track and siding switches, main track and siding switch throwing and locking mechanisms and connections between the main track switch and siding switch interfering with movement of the siding switch throwing mechanism when the main track switch is in normal position and interfering with replacement of the main track switch to normal when the side track switch is in other than normal position.

15. In a cross-over between two main tracks, the combination of two main track switches, two main track switch throwing mechanisms, interlocking between two main track throw mechanisms requiring throwing of one to normal after it has been thrown

for the cross-over before the other can be thrown to normal and common locking mechanism for both main track switches.

16. In a cross-over between two main tracks, main track switches in the two main tracks and switch operating mechanisms for the two switches comprising a throwing lever and connections from the throwing lever to the switch point to throw the switches, common locking mechanism for the two switches and interlocking between the locking mechanism and each of the throwing levers.

17. In a cross-over between two main tracks, main track switches in the two main

tracks, apertured locking rods from the two switches, common locking mechanism for each of the switches terminating in bars entering the locking rods, switch operating mechanisms, one for each switch, comprising pivoted switch throwing levers and connections from the switch throwing levers to the switches and interlocking connections between the locking bars and the switch throwing levers preventing movement of the switch throwing levers until the locking bars are withdrawn.

CHARLES C. THORN.
